Primary Examiner — George D Kirschbaum(57) **CLAIM**

The ornamental design for a doorbell, as shown and described.

DESCRIPTION

FIG. 1 is a front, side, and top perspective view of a doorbell embodying the new design;

FIG. 2 is a back, side, and bottom perspective view thereof;

FIG. 3 is a front view thereof;

FIG. 4 is a back view thereof;

FIG. 5 is a first side view thereof, the second side view being a mirror image;

FIG. 6 is a top view thereof; and,

FIG. 7 is a bottom view thereof.

The uniform repeating broken lines are included for the purpose of illustrating portions of the "article" and form no part of the claimed design. The dash-dot-dash lines represent the boundary of the claim.
